[57] **ABSTRACT**

This invention relates to a programmed positioning device for the needle selection jacks in a jack support wheel of a circular jacquard knitting machine. In the device of the invention the jack support wheel is supported by a support frame and is intermittently rotated so that each radial slot of the wheel is brought successively into a predetermined stop position. Furthermore, the support frame slidably supports radially directed thrust means, which are movable towards the wheel in order to be radially inserted into each slot and to engage one or both the jacks housed within the slot.

PROGRAMMED POSITIONING DEVICE FOR THE NEEDLE SELECTION JACKS IN A JACK SUPPORT WHEEL OF A CIRCULAR JACQUARD KNITTING MACHINE

The present invention relates to a programmed positioning device for the needle selection jacks in a jack support wheel of a circular jacquard knitting machine.

Circular jacquard knitting machines are notably provided with wheels which support a plurality of jacks the purpose of which is to regulate the selection of the needles for making the required patterns on the fabrics. Normally these wheels are provided with a plurality of radial equidistant slots inclined to the axis of the wheel, in each of which is housed in a radially slidable manner a pair of superimposed jacks, which can move between a first position in which the outside ends of the jacks are both substantially in line with the external profile of the wheel, a second position in which a first jack is withdrawn with respect to the second, and a third position in which both jacks are withdrawn with respect to the first stated position. The distribution of the positions pre-chosen for the various pairs of jacks housed in the various radial slots of the wheel evidently determines the pattern of the finished fabric.

Until a short time ago, each time said distribution of the jack positions in a wheel had to be changed (for example when passing from one pattern to another), it was necessary to completely dismantle the wheel, remove the jacks from their seats and replace them in their new radial chosen positions. This evidently led to large loss of time and resultant undesirably high production costs.

At the present time undoubted progress has already been made, in the sense of providing wheels capable of enabling all the jacks to be returned to their initial position without the need to dismantle the entire wheel. This has been obtained by constructing the wheel in two superimposed parts which are rotatable one with respect to the other and by the use of a suitable key which, by rotating together with the rotatable part, acts on the inside ends of the jacks (supported by the fixed part) in such a manner as to thrust them towards the previously defined initial position.

However the problem of the new positioning of the jacks has remained unsolved, and this for wheels of the aforementioned new type is done by manually inserting a peg into the various slots of the wheel.

It can be easily imagined that this leads to a considerable loss of time and a constant danger of error (which would make it necessary to re-position all the jacks).

The object of the present invention is therefore to provide a device which enables the jacks of a jack support wheel of a circular jacquard knitting machine to be very easily and rapidly positioned.

This object is attained by the device according to the invention which in its most general lines comprises a support frame for the wheel, means for producing angular stepwise forward movements of the wheel in such a manner that each of the radial slots of the wheel is brought successively into a predetermined position in which it is momentarily halted, and thrust means slidably supported by said support frame in a position aligned with a slot as it comes in turn into said predetermined position such that following a control action resulting in their axial movement they are inserted radially into said slot and engage with both the jacks

housed in the slot or, selectively, only with said first jack, so as to move the jacks from the first to the third or to the second of the aforementioned positions respectively.

5 Two embodiments of the device according to the invention are shown by way of example in the accompanying drawings, with reference to which they are described hereinafter in detail for a better understanding of the characteristics of the present invention.

10 In the drawings:

FIGS. 1, 2 and 3 are three different perspective views of a first device according to the invention;

15 FIGS. 4 and 5 are perspective views showing the manner by which it is possible to select the two types of operation of the thrust means which determine the movement of the jacks into the third or second of their assumable positions respectively;

20 FIG. 6 is a cross-sectional view of said thrust means on the line VI—VI of FIG. 7, said thrust means being considered in the rest position shown in FIGS. 1-3;

FIG. 7 is a longitudinal sectional view of said thrust means on the line VII—VII of FIG. 6;

25 FIG. 8 is a cross-sectional view of said thrust means on the line VIII—VIII of FIG. 9, said thrust means being considered in their working position as shown in FIG. 5;

FIG. 9 is a longitudinal sectional view of said thrust means on the line IX—IX of FIG. 8;

30 FIG. 10 is a partly full and partly sectional view of a jack support wheel in which the jacks housed in the selective slot are in their first position;

35 FIGS. 11 and 12 are detailed views on an enlarged scale of a slot of the jack support wheel in which the jacks, following the action of the thrust means, have been moved into the third and second positions respectively;

40 FIG. 13 is the basic circuit diagram of the electrical circuit associated with the device shown in the preceding figures;

45 FIG. 14 is a perspective view of a second device according to the invention;

FIGS. 15, 16 and 17 are perspective views on an enlarged scale showing the method of operating the thrust means and relative operating means included in the device of FIG. 14;

50 FIGS. 18 and 19 are substantially plan views of said thrust and operating means of FIGS. 15, 16 and 17;

FIG. 20 is a further perspective view of said thrust and operating means of FIGS. 15, 16 and 17.

55 The device shown in FIGS. 1-13 comprises a base frame 1, on which are fixed an electrical supply transformer 2, a rectangular frame 3 and a bridge frame 4.

The frame 3 (FIGS. 1-3) supports rotatably a shaft 5 on which the jack support wheel to be adjusted, indicated overall by the reference numeral 20, is removably fixed by means of wedge blocks 18. As can be seen from FIGS. 10-12, the jack support wheel 20 is of the type (conventional) provided with a plurality (normally 144) of radial slots 33 inclined to the axis of the wheel, in each of which are housed two superimposed jacks 21 and 22 which together can assume three different positions defined by the mutual engagement between a projection 23 on the jack 21 and a notch 24 on the jack 22, by the selectively obtainable engagement between a projection 25 on the jack 21 and one or other of two annular grooves 26 and 27 on a ring 28,

60 and by the selectively obtainable engagement between

a projection 29 on the jack 22 and one or other of two annular grooves 30 and 31 on a ring 32. By the effect of these engagements, the two jacks may be moved between a first position in which their outside ends are substantially in line with the external periphery of the wheel (FIG. 10), a second position in which the jack 22 is withdrawn with respect to the jack 21 (FIG. 12) and a third position in which both jacks are withdrawn with respect to the first said position (FIG. 11). The wheel 20 is of conventional type and available commercially, and consequently will not be described here in detail; for the purposes of the present invention it is sufficient to mention that besides that stated previously regarding the jacks, all the jacks can be returned to the position shown in FIG. 10 by simply rotating a rotatable part 34 (which carries the rings 28 and 32) with respect to a fixed part 35 (which carries the jacks) by means of a zeroing bridge key engaged in two diametrically opposite holes 36 and 37 (FIGS. 1-3) and provided with a tooth capable of acting on the inner ends of the jacks in order to push them all radially towards the position shown in FIG. 10. As mentioned earlier, the particular manner of zeroing the jacks is of no consequence. The jacks could be zeroed manually or by means of manually controlled tools upon disassembling of the pattern wheel as, for example, is explained in U.S. Pat. No. 3,788,101 in the name of Paolo Orizio. In the latter patent and in conventional pattern wheels of the type disclosed therein and herein one end of the bridge key (not shown), more precisely the end which is inserted into the hole 36, is provided with a properly shaped tooth which during rotation of the rotatable part 34 of the pattern wheel caused by means of the bridge key is capable of sequentially engaging the inner ends of all of the retracted jacks 22, when positioned as shown in FIGS. 11 and 12, to push them and consequently the possibly retracted jacks 21 (FIG. 11) toward the zeroed position shown in FIG. 10. The movement of the jacks 21 between the positions of FIGS. 10 and 11 is permitted as a result of the provision of an unreferenced spring between the ring 28 and the bottom wall of the recess in which the same ring is located, while the movement of the jacks 22 between the position of FIG. 10 and the positions of FIGS. 11 or 12 are allowed as a result of the elasticity of the material of the ring 32 or as a result of the provision of an unillustrated spring between the ring 32 and the bottom wall of the recess in which the ring 32 is located. The latter-mentioned spring corresponds to the spring 25 of the U.S. Pat. No. 3,788,101. Furthermore it should be noted, as shown in FIGS. 1, 3 and 8, that each of the slots 33 is provided with an extension 19 into which a traversable tongue rigid with a pushbutton 38 provided with a thrust spring 39 may be inserted so as to avoid any rotation of the wheel 20.

On the shaft 5 is fixed (FIGS. 1-3) a wheel with unidirectional toothing 6, its number of teeth being equal to the number of the radial slots of the wheel 20. A pawl 8 pivoted on a double lever 9 pivoted at 10 to the upper base of the frame 3 is kept engaged with the periphery of the wheel 6 by means of a spring 7. The lever 9 is operated by an electromagnet 11, the mobile core of which is connected to the lever 9 by a rod 12. When the electromagnet is de-energized a spring 13 keeps the lever 9 in a rest position defined by its contact with a ratchet 14. A further pawl 16 pivoted at 17 on a bracket 40 fixed to the frame 3 is also kept engaged

with the periphery of the toothed wheel 6 by means of a spring 15. As shown in FIG. 2, the pawl 16 (and likewise the pawl 8) is engaged with the toothed wheel 6 in such a manner as to allow anti-clockwise rotation (relative to FIG. 2), but not clockwise rotation.

The frame 4 (FIGS. 1-9) supports means for setting the thrust means to selectively move one or both of the jacks including a substantially trapezoidal block 41, provided with an upper base hollowed out in the form of an arc of a circle, with which is adjustably engaged a semicylindrical frame 42. The adjustable engagement between the block 41 and frame 42 is given by a screw 43 fixed to the block 41 and inserted in a transverse groove 44 on the frame 42. On the frame 42 is fixed a plate 45 on which is fixed a further plate 46 with which a further plate 47 is slidably engaged (FIGS. 7 and 9). The plate 47 is normally held against a first stop element 48 by a spring 49 (FIG. 6) and may be moved into engagement with a second stop element 50 (FIG. 8) by pushing downwards a lever 51 (FIGS. 4 and 5) fixed on a rotatable shaft 52 coupled by a square coupling 53 to a fork 54 locked on a gudgeon pin 55 fixed to the plate 47 and passing through central bores 56 and 57 in the plate 46 and in the plate 45 (FIGS. 6-9). The purpose of the plate 47 is to support thrust means 58, which consist of a cylindrical shaft 59 housed in a longitudinally slidable manner in the cylindrical cavity formed between two complementary blocks 60 and 61. Motion imparting means in the form of the shaft 59 and/or opposed by a spring 63 effects sliding motion to a flat tongue 64 of the thrust means 58. The shaft 59 terminates to the front with the flat tongue 64, when the knob 62 is at rest, rests completely housed between two frustum extensions 65 and 66 of the blocks 60 and 61 (FIG. 7) and when the knob 62 is pushed, emerges from said extensions and enters that slot 33 of the wheel 20 which in that moment is in a position facing said tongue (FIGS. 4, 5 and 9). As shown in FIGS. 4-9, a pin 67 projects laterally from the shaft 59 and, passing through a slot 68 formed in the blocks 60-61 is arranged to engage with a microswitch 69 on the frame 42 when the shaft 59 is pushed forwards by pressing the knob 62.

The device described also comprises an electrical control assembly, two components of which are the transformer 2 and electromagnet 11 previously mentioned. As shown in FIG. 13, the primary winding of the transformer 2 is connected by way of a main switch 90 (also shown in FIGS. 1-2) to two terminals 91 and 92 together constituting a normal plug for connection to the electric mains. The secondary winding of the transformer 2 is connected to the two alternating current inlets of a bridge rectifier 93, the direct current outlets of which are connected to the electromagnet 11 by way of the normally closed microswitch 69, a normally closed pushbutton 94 (also shown in FIGS. 1, 2, 3, 7 and 9) and a switch 95, all connected in series. This latter, which in FIG. 13 is shown in the rest position, is connected to an impulse counter (also visible in FIGS. 1 and 3) which is able to move it when the number of impulses counted reaches a predetermined value. This impulse counter is connected in the circuit of FIG. 13 in parallel with the electromagnet 11. Finally the circuit of FIG. 13 comprises a lamp 97 (also visible in FIG. 2) which becomes connected in parallel when the switch 95 is moved into the position dictated by the counter 96.

The operation of the device shown in FIGS. 1-13, based on the described structure, is as follows.

Initially the jack support wheel 20 is arranged on the shaft 5 in such a manner that one of its slots 33 is in exact alignment with the tongue 64; the thrust means 58 are also adjusted in this sense, i.e. the inclination of the tongue 64 is adjusted utilising the engagement existing between the screw 46 and groove 44 (FIGS. 6 and 8). Having done this the main switch 90 is closed, by which means the counter 96 is made ready for counting and the electromagnet 11 is energised, which by attracting the rod 12 towards itself makes the pawl 8 cause the toothed wheel 6 (and hence the wheel 20) to make an angular forward movement of one step in the anticlockwise direction relative to FIG. 2.

At this point it is possible to act in three different ways according to the position required for the two jacks housed in the slot of the wheel 20 which has been selected. If they are to remain in the position shown in FIG. 10 (previously given to all the jacks by using the zeroing key in the described manner), the thrust means 58 are simply left at rest and the wheel 20 is made to make a further angular forward movement by pushing and then releasing the pushbutton 94 (the electromagnet 11 is first deenergised, returning the pawl 8 to the position shown in FIG. 2, and is then re-energised to cause a further forward movement of the toothed wheel 6 by one step); if however the two jacks are to be put into the position shown in FIG. 11 (both withdrawn), the knob 62 is simply pushed so that the tongue 64 penetrates into the selected slot (FIG. 4) and pushes both jacks backwards as in FIG. 10 (as the peg 67 opens the microswitch 69 the electromagnet 11 is further de-energised and then re-energised, and hence causes a further angular forward movement of the wheel 20); if only the jack 22 is to be withdrawn, as in FIG. 12, the lever 51 is first operated (arranged so that it can be operated by the same hand which operates the knob 62 and simultaneously with it) so that the sliding plate 47 is pushed against the stop element 50 (FIG. 8) and then the knob 62 is pressed with the result that the tongue 64 engages only with the jack 22 and leaves the jack 21 where it is (FIGS. 5 and 12). Hence one or other of a plurality of different distributions is obtained for the various jacks of the wheel 20, i.e. a different working programme for the wheel, according to the chosen requirements for each of the slots of the wheel 20 which are brought in turn into alignment with the tongue 64 (it should be noted that when the thrust means 58 are operated for inserting the tongue 64 into one of the slots 33, the pushbutton 38 is pushed so that the tongue which is rigid with it becomes inserted into one of the slots 19 and keeps the wheel 20 locked as the thrust means 58 are operated).

The programming operation for a jack support wheel finishes when the number of impulses counted by the counter 96 reaches a predetermined limit equal to the number of programmable slots in the jack support wheel. At this point the switch 95 is moved towards the lamp 97 with the result that this latter lights and current is removed from the electromagnet 11. It is then possible to remove the already programmed wheel and replace it with another to be programmed (in addition the counter 96 is zeroed by known means).

The device shown in FIGS. 14-20 comprises a base frame 101 on which are fixed a triangular frame 102, a rectangular frame 103 and a bridge frame 104.

The frame 102 rotatably supports a shaft 111 driven by a handle 116 which after each complete turn can be removably locked in the rest position shown in FIG. 14. A worm 117 is keyed on the shaft 111.

5 The frame 103 rotatably supports a shaft 118 on which is removably fixed a jack support wheel exactly similar to that shown in FIGS. 10-12 and because of this indicated by the same reference numeral 20. On the shaft 118 is fixed a further wheel 138 exactly similar to the wheel 20 and in phase with it, and which is engaged with the worm 117 so as to make the slots 33 move forward angularly by one step for each complete turn of the worm 117.

The support frame 104 supports a rectangular frame

15 70 on which is arranged in a positionable manner (bolts 71 in loose slots in the upper cross member of the frame 70) an element in the form of a cross 72 fixed to a substantially square frame 73. This latter frame supports slidable thrust means 82, 83 operated by a lever

20 74 which moves between a position of engagement with a first extension 75 of an opening 76 in the frame 73 (FIGS. 17 and 19), a position of engagement with a second extension 77 of the opening 76 (FIGS. 16 and 18) and an intermediate rest position (FIG. 15). The

25 The opening 76, the extensions 75, 77 thereof, and the lever 74 to define means for setting the thrust means 82, 83 at a desired position to engage the lever 74 to make these movements because it is pivoted in a vertical axis and in a horizontal axis at the cylinder 78 (in

30 which is housed a sphere which forms a ball joint for a cupped appendix of the lever 74, FIG. 20) and at the other cylinder 79 housed in a seat defined by a frame 80 (FIGS. 15-19). The end of the lever 74 and/or the knob (unnumbered) attached thereto constitute means for imparting axial motion to the thrust means 82, 83 through the lever 74 and a tooth 81 carried thereby. The tooth 81 is rigid with the lever 74, and according to whether the lever is in the position shown in FIG. 18

35 or in the position shown in FIG. 19, it engages either with both or only with the upper of two half cylinders 82 and 83 independently slidably axially in a cylindrical core 84 which is positionable with respect to the frame 73 after unlocking a lever 85. With the two half cylinders 82 and 83 are rigid respective coplanar tongues 86

40 and 87 which are aligned one with the one and the other with the other of two jacks (21 and 22) housed in the slot of the wheel 20 selected in turn.

The operation of the device shown in FIGS. 14-20 is as follows. The various slots in the wheel 20 are 45 brought in turn by the handle 116 into a position facing the tongues 86 and 87. For every slot selected, if the lever 74 is left in the rest position shown in FIG. 15, neither of the two tongues becomes inserted into the selected slot and the relative jacks remain in the position shown in FIG. 10; if however the lever 74 is moved into the position shown in FIGS. 17 and 19, the tooth 81 engages only with the half cylinder 82, because of which only the tongue 86 becomes inserted into the selected slot so as to bring the jack 22 into the position shown in FIG. 12; finally if the lever 74 is moved into the position shown in FIGS. 16 and 18, the tooth 81 engages with both the half cylinders 82 and 83, because of which both the tongues 86 and 87 are inserted into the selected slot so as to bring the two jacks 21 and 22

50 into the position shown in FIG. 11. Thus by merely operating the lever 74 it is possible to make any adjustment for the wheel being programmed.

What we claim is:

1. A programmed positioning device for the needle selection jacks in a jack support wheel of a circular jacquard knitting machine of the type provided with a plurality of equidistant radial slots in each of which is housed in a radially slidable manner a pair of superimposed jacks movable between a first position in which the outer ends of the jacks are both substantially in line with the external profile of the wheel, a second position in which a first jack is withdrawn with respect to a second jack and a third position in which both jacks are withdrawn with respect to the first stated position, characterised in that said programmed positioning device comprises a support frame for the wheel, means for producing angular stepwise forward movements of the wheel in such a manner that each of the radial slots of the wheel is brought successively into a predetermined position in which it is momentarily halted, thrust means slidably supported by said support frame in a position aligned with a slot as it comes in turn into said predetermined position, means for setting the thrust means to selectively move one or both of the jacks, and means for imparting axial movement to said thrust means whereby said thrust means is inserted radially into said slot and engage either with both the jacks housed in the slot, or selectively, only with said first jack, so as to move the jacks from the first to the third or to the second of the aforementioned positions respectively.

2. A device as claimed in claim 1, in which said thrust means is an elongated flat tongue movable along its own axis, said setting means include means for moving said tongue transverse to its own axis, and the extent of the transverse movement being such as to enable the tongue to engage only with one of the jacks housed in the selected slot when the tongue is subjected to axial movement following transverse movement, whereas only the axial movement without the addition of transverse movement causes the tongue to engage with both jacks of the selected slot.

3. A device as claimed in claim 2, comprising means sensitive to the axial movements of the tongue operatively connected to said angular stepwise producing means to make said wheel move forward by one step for each axial movement of the tongue towards the selected slot, and control means for making said angular stepwise producing work stepwise independently of the operation of the tongue.

4. A device as claimed in claim 2 wherein said setting means additionally includes a slide, means mounting said slide for transverse movement relative to the axial movement of said tongue, said slide carries said tongue, and means coupling a lever to said slide whereby movement imparted to said lever imparts said transverse movement to said tongue through said slide.

5. A device as claimed in claim 4 wherein said tongue is carried by a shaft in part defining said thrust means, said shaft terminating in a knob, and said knob and lever are positioned in such a manner that they can both be operated by the same hand.

6. A device as claimed in claim 1 wherein said thrust means is a pair of flat tongues, each tongue being disposed in such a manner as to engage with only one of the two jacks housed in the selected slot, and means for aligning said setting means for contacting both or only one of said tongues.

7. A device as defined in claim 6 wherein said movement imparting means and setting means include a common lever.

8. A device as defined in claim 7 including means pivotally mounting said lever for pivotal movement in a plane generally transverse to the axis of movement of said thrust means.

9. A device as defined in claim 8 wherein said pivotally mounting means also mounts said lever for pivotal movement in a plane generally common to the axis of movement of said thrust means.
